UNITED STATES PATENT OFFICE.

HENRY CUTLER, OF NORTH WILBRAHAM, MASSACHUSETTS.

GRAIN-DRIER.

SPECIFICATION forming part of Letters Patent No. 269,644, dated December 26, 1882.

Application filed June 28, 1882. (No model.)

To all whom it may concern:

Be it known that I, HENRY CUTLER, of North Wilbraham, in the county of Hampden and State of Massachusetts, have invented a new and Improved Grain-Drier, of which the following is a full, clear, and exact description.

My improvements relate to grain-driers of the class shown in Letters Patent granted to me September 20, 1881, and numbered 247,318, in which the grain is passed through a revolving cylinder heated by steam-pipes.

The object of my present invention is to provide for the construction of driers with large capacity, in which the temperature can be raised to a high point; also, to provide for expansion and contraction without any injury to the machine or the liability of breaking joints and consequent leaking.

To these ends my invention consists in the novel features of construction hereinafter described and claimed.

Reference is to be had to the accompanying drawings, forming part of this specification, in which similar letters of reference indicate corresponding parts in all the figures.

Figure 1 is a longitudinal section of my improved steam-drier. Fig. 2 is a transverse section on line $x-x$ of Fig. 1, showing the steam-head. Fig. 3 is a transverse section on line $y-y$ of Fig. 1. Fig. 4 is a longitudinal section of a plug for the admission of steam and escape of water through the hollow journal of the drier; and Fig. 5, a transverse section of the plug on an enlarged scale on line $z-z$, Fig. 4.

A is the cylinder, constructed of wood, and provided with steam-head B at its lower end and head C at its upper end. The steam-head B is formed double or hollow, with a central partition, a , and radial partition-plates b , by which four chambers are formed at each side of the partition-plate a , of which the chambers at the outside (marked c) are in the form of sectors separated by the spaces d . The inside chambers between partition a and back plate, d' , are marked c' .

The partition-plate a is formed with numerous holes that receive the ends of pipes f , which pipes extend lengthwise of the cylinder. The inner or back plate, d' , of the steam-head is apertured to correspond with the partition-plate a , but the holes are of larger size, to receive the pipes g that receive the pipes f . The

opposite ends of these pipes g are received and supported by an apertured disk, C , and these ends are closed. It will be seen that by this construction the smaller pipes f connect with the outer chambers, c , while the larger pipes g are open to the chambers c' at the inner side of the partition-plate a and back plate, d' .

The head B is formed with a hollow journal, i , by which the lower end of the cylinder is supported in the bearings j . In this hollow journal is fitted the steam-plug D, that is formed to allow the inlet of steam into the cylinder and the outlet of water therefrom, as next described.

The plug D is formed with a central passage, k , for steam, and a side passage, l , for water. At its outer end the plug has a side aperture, k' , for connection with the steam-pipe, so that the steam entering the passage k enters the

chambers c of the steam-head, and at the end of the water-passage l is an opening, l' , for connection to a steam-trap. The inner end of this passage l opens out upon the surface of the steam-plug so as to communicate with the inclined passages m that are formed in the hollow journal i , and through the steam-head B to

the inner chambers, c' , with which the pipes g communicate. By this construction the steam entering by passage k to the steam-head passes

into the pipes f , and the return steam and water of condensation are carried by the pipes g to the inner chambers, c' , of the steam-head, and from thence pass through the passages m to the passage l of the steam-plug. The passage l communicates with each passage m once during a rotation of the cylinder.

The several chambers c' at the inside of the partition-plate a , and between it and back plate, d' , are connected together at their inner ends, and pockets are thereby formed similar to those represented at n , Fig. 2, which serve to collect the water of condensation, and by the passages m , communicating with these pockets, the water is carried off.

The steam-plug is provided with annular packing o to prevent the escape of steam. The outer packing is compressed by a gland, p^2 , applied around the outer end of the plug, and the inner packing, o , is held in place by a bail, p' , connected to a rod, p^1 , that passes through the center of the plug to the outside, where the rod is provided with a nut for tightening the packing.

- The steam-head B and upper head, C, are connected together by stringers *q* of wood, which are bolted to them, the stringers being thereby held securely by a material that is not affected by heat. Iron segments *j* pass from one stringer to the next, and these segments serve to support the outer wooden casing as attached around the segments by hoops *u*, thereby giving the cylindrical form and required strength to the casing.
- The shaft *w* of the cylinder is bolted to the inner side of the steam-head B, and passes through the upper head, C, where it is formed as a journal for support of the cylinder. The shaft is fitted interiorly of the cylinder with partitions *s*, which extend the whole length of the cylinder, so that they serve to divide the interior into four separate sections, each section containing a cluster of the tubing *f g* and a ventilating-aperture, *t*, Fig. 1, so that each section constitutes a separate drier, and the grain being divided equally by the partitions the weight is balanced, so that less power is required to operate the drier.
- The separate compartments are fed with grain by means of the buckets *u'*, which are fastened to the outside of the cylinder next to the disk C, and in the rotation of the cylinder these buckets pass successively through a trough *v* under the cylinder to which the grain is supplied.
- The apertures in the cylinder A beneath the buckets are fitted with inclined plates *x*, by which the grain is moved forward. These plates also cover the apertures, so that the grain cannot pass out of the cylinder when the buckets are at the under side of said cylinder.
- Any suitable outlet for the grain from the cylinder after it is dried may be provided, as I do not seek to make any improvement in that part of a drier.

Having thus described my invention, I claim as new and desire to secure by Letters Patent—

1. The cylinder having the hollow steam-

head B, with the apertured plates *a d'*, partition-plates *b*, four chambers on each side of plate *a*, the pipes *f g*, and the disk C, as shown and described.

2. The cylinder-head B, having chamber *c c'*, hollow journal *i*, with inclined passages *m*, and bearings *j'*, in combination with a plug, D, having the central steam-passage *k*, lateral water-passage *l*, and openings *k' l'*, as shown and described.

3. The combination, with the head B, having passages *m*, back plate, *d'*, and the plate *a*, of the chambers *c'*, connected at their inner ends to form pockets *n*, and communicating with said passages, as shown and described.

4. The combination, with the packing, of the gland *p'* around the outer end of the plug D, the bail *o'*, and the rod *p'*, passing through the center of plug, as described.

5. In grain-driers, the combination, with the steam-head B, having the hollow journal *i* and passages *m*, of the steam-plug D, provided with the separate passages *k l* for steam and water, substantially as shown and described.

6. In grain-driers, the steam-head B, constructed with the separate steam and water chambers, and the hollow journal *i* in one piece, substantially as shown and described.

7. In grain-driers, the steam-plug D, having the passages *k l*, and provided with the packings *o p*, in combination with the hollow journal *i*, substantially as described.

8. In grain-driers, the combination of the buckets *u'*, plates *x*, and trough *v*, substantially as described, for operation as set forth.

9. In grain-driers, the feed-buckets *u'*, for suspending the cylinder, in combination with the cylinder A and trough *v*, substantially as shown and described.

HENRY CUTLER.
